(57) **CLAIM**

The ornamental design for a card case with band closure, as shown.

DESCRIPTION

The patent or application file contains at least one drawing executed in color. Copies of this patent or patent application publication with color drawing(s) will be provided by the Office upon request and payment of the necessary fee.

FIG. 1 is a perspective view of a first embodiment showing the top, right and front views of the inventive card case with band closure.

FIG. 2 is a perspective view of a first embodiment showing the top, right and front views of the inventive card case with band closure, shown in an environment of use.

FIG. 3 is a perspective view of a first embodiment showing the top, right and front views of the inventive card case with band closure, shown with an elastic band off and the case partially open, shown in an environment of use.

FIG. 4 is a top view of FIG. 1.

FIG. 5 is a top view of FIG. 2.

FIG. 6 is a bottom view of FIG. 1.

FIG. 7 is a right view of FIG. 1.

FIG. 8 is a right view of FIG. 2.

FIG. 9 is a left view of FIG. 1.

FIG. 10 is a back view of FIG. 1.

FIG. 11 is a front view of FIG. 1.

FIG. 12 is a perspective view of a second embodiment showing the top, right and front views of the inventive card case with band closure, and the features represented by a color shown in the colored portion of the design.

FIG. 13 is a perspective view of a second embodiment showing the top, right and front views of the inventive card case with band closure, shown in an environment of use, and the features represented by a color shown in the colored portion of the design.

FIG. 14 is a perspective view of a second embodiment showing the top, right and front views of the inventive card

case with band closure, shown in an environment of use, shown with an elastic band off and the case partially open, and the features represented by a color shown in the colored portion of the design.

FIG. 15 is a top view of FIG. 12.

FIG. 16 is a top view of FIG. 13.

FIG. 17 is a bottom view of FIG. 12.

FIG. 18 is a right view of FIG. 12.

FIG. 19 is a right view of FIG. 13.

FIG. 20 is a left view of FIG. 12.

FIG. 21 is a back view of FIG. 12; and,

FIG. 22 is a front view of FIG. 12.

The evenly dashed broken lines depict portions of the article and form no part of the claim. The dash-dot-dash broken lines depict environment and form no part of the claim.
